CLAIM

The ornamental design for an engine component, as shown and described.

DESCRIPTION

FIG. 1 is a side perspective view of an engine component in accordance with the present design.

FIG. 2 is a side view of the engine component.

FIG. 3 is a side view of the engine component.

FIG. 4 is a side view of the engine component.

FIG. 5 is a side view of the engine component.

FIG. 6 is a top view of the engine component; and,

FIG. 7 is a bottom view of the engine component.

This article is not limited to the scale shown herein.
